UNITED STATES PATENT OFFICE.

FRANZ XAVER KOMAREK, OF VIENNA, AUSTRIA-HUNGARY.

STEAM-BOILER.

No. 825,062.

Specification of Letters Patent.

Patented July 3, 1906.

Application filed February 3, 1906. Serial No. 299,327.

To all whom it may concern:

Be it known that I, FRANZ XAVER KOMAREK, manufacturer of machines, a subject of the Emperor of Austria-Hungary, and a resident of Vienna, in the Empire of Austria-Hungary, X Quellengasse 55, have invented a Steam-Boiler with an Internal Fire-Box; and I do hereby declare the following to be a full, clear, and exact description of the invention, such as will enable others skilled in the art to which it appertains to make and use the same.

My invention relates to steam-boilers, and especially to boilers with an internal fire-box and provided with water-tubes.

The object of my invention is to provide an effective water circulation in a boiler the fire-box of which is surrounded with water by a peculiar arrangement of water-tubes.

The invention further comprises means whereby said water-tubes and the interior of the boiler are easily accessible without endangering the tightness of the boiler, as well as the combination of the aforesaid parts, with means for superheating the steam generated within the boiler and, furthermore, with parts securing a greater durability of the boiler and the fire-box.

In the drawings a boiler of an upright type is shown in Figure 1 in a vertical section and in Fig. 2 in a horizontal section.

For the purpose of more clearly showing certain details the thickness of the central plate 24 of the outer shell is shown slightly exaggerated in Fig. 1.

The boiler consists of the outer shell 1, within which the fire-box 2 is arranged. The fire-box is preferably made of corrugated steel plates, and its lower rim is riveted to the outer shell, while the top of the box is formed by the part 3, which is connected by a pipe 4 with the top of the outer shell 5. In this way the water-chamber is separated from the interior of the fire-box; but in order to provide a greater heating-surface two sets of water-tubes project into the passage of the heating-gases. One set of these tubes 6 extends at one end through the top of the fire-box and at the other end through the side thereof, and the tubes 7 of the other set extend through the side thereof.

The boiler is provided with a fire-door 8, which leads to the fireplace, where a grate 9 is arranged which closes the fire-box at the lower end.

The heating-gases flow around the bunches

of water-tubes to the flue-pipe, whereto a smoke-stack 10 is attached, the draft of which may be increased by the exhaust-pipe 11.

60

The steam generated within the boilers passes through pipes 12 13 into a superheater, which consists of two coils of piping 14 15, centrally arranged within the flue-pipe and the fire-box in the passage of heating-gases. The two coils of piping are further connected with a steam-chamber or header 16.

65

The outer shell of the boiler is provided with a blow-off 17 and manholes 18 18'. Other openings 19 20 are arranged opposite to water-tubes in order to permit of access to the water-chamber and the water-tubes, which may be cleaned or tightened through these openings.

70

There might be provided a hole for each tube or one big opening for a greater number of tubes; but as the first arrangement involves many openings close together, while the other one requires large openings, both of which are hard to keep tight, I prefer to arrange cleaning-holes whereof each serves for a few tubes only, preferably for two. The tubes are arranged in such a way that two or a few of them, running together at an angle α , as shown in Fig. 1, thereby face a cleaning-hole arranged opposite these converging tube ends.

75

In order that the outer shell may be easily removed, the same is divided in two parts 1 and 21, which are connected by flanges 22 23. 90 The division is above the fire-door, so that by removing the upper part of the tubular shell the ends of the water-tubes, as well as the upper part of the fire-box, are accessible. Another flange 26 connects the annular top 95 of the boiler-shell with the fire-box flue 4, whereby after cutting the rivets, which are passed through said top and the flange, the boiler-top may be removed without damaging the flue or the flue may be removed 100 without injuring the top.

95

For that part of the outer shell where the cleaning-holes 19 20 are arranged I prefer to take a special plate 24, and I also prefer to arrange a special tubular part 25 for the fire-box, in which the lower ends of all or of some of the water-tubes are secured, because such arrangement permits of a better working; but corrugated plates only may also be used for the whole wall of the fire-box.

105

The water-tubes are radially arranged, or nearly so, and as they come in close contact

110

with the burning gases they cause a lively circulation of the water in the water-chamber, which circulation is increased by the peculiar arrangement of the water-tubes, by 5 which different portions of the water in the annular part of the water-chamber are brought in communication not only with each other, but also with the water parts above the top plate of the fire-box. Consequently 10 the generation of steam is more general, and thereby quicker.

The danger that the tubes may be covered by soot and ashes is avoided, as enough space is left between the tubes to give a sufficient draft. 15

My peculiar arrangement of the ends of the tubes and the holes in the outer shell provides effective means by which the tubes are accessible for cleaning and tightening without 20 endangering the tightness of the boiler. The tubes are removed through the fire-box.

My invention may not only be applied to boilers of an upright type, but to fire-box boilers of any system.

25 What I claim as my invention, and desire to secure by Letters Patent, is—

1. In a steam-boiler an outer shell and an internal fire-box, corrugated plates forming the wall of said fire-box, in combination with 30 a flat top for said fire-box, water-tubes in said fire-box, some of said tubes having both ends secured in the corrugated wall-plates of said box and others of tubes having one end in the wall-plates of said fire-box and the other end in the flat top plate of said box, the cylindrical outer shell having cleaning-holes opposite to the ends of the tubes, substantially as described.

2. In a steam-boiler an outer shell and an 40 internal fire-box, corrugated plates forming the wall of said fire-box, in combination with a flat top for said fire-box, water-tubes in said fire-box, some of said tubes having both ends secured in the corrugated wall- 45 plates of said box and others of tubes having one end in the wall-plates of said fire-box and the other end in the flat top-plate of said box, and the cylindrical outer shell having cleaning-holes, the ends of a bunch of neighboring tubes converging toward each opposite hole in the outer shell, substantially as described.

50 3. In a steam-boiler an outer shell and an internal fire-box, corrugated plates forming

the wall of said fire-box, in combination 55 with a flat top for said fire-box, water-tubes in said fire-box, some of said tubes having both ends secured in the corrugated wall-plates of said box and others of tubes having one end in the wall-plates of said fire-box 60 and the other end in the flat top plate of said box, the cylindrical outer shell having cleaning-holes, the ends of a bunch of neighboring tubes converging toward each opposite hole in the outer shell and two superheater-coils 65 within said fire-box, substantially as described.

4. In a steam-boiler the combination of an outer shell comprising two parts, flanges connecting said two parts, an internal fire-box, 70 corrugated plates for the wall of said box, a plain tubular part in said fire-box, wherein one end of the water-tubes is arranged, a top plate to the fire-box, a flue-pipe upon said top plate, a flange riveted to said flue-pipe 75 and connecting it with the top plate of the outer shell, water-tubes within the fire-box, and a superheater within said flue-pipe, said outer shell having said fire-box and cleaning-holes in the cylindrical part thereof opposite 80 to the ends of said tubes, substantially as described.

5. In a steam-boiler the combination of an outer shell comprising two parts, flanges connecting said two parts, an internal fire-box, 85 corrugated plates for the wall of said box, a plain tubular part in said fire-box, wherein the water-tubes are secured, a top plate to said fire-box, a flue-pipe upon said top plate, a flange riveted to said flue-pipe and connecting 90 it with the top plate of the outer shell, water-tubes within the fire-box connecting points of the cylindrical wall of the fire-box, tubes connecting points of the cylindrical wall with points of the top plate of said fire-box, said tubes forming bunches with the ends running together and toward cleaning-holes arranged in the cylindrical part of the outer shell and superheater-coils within said flue-pipe and said fire-box, substantially as 95 described.

In testimony whereof I have signed my name to this specification in the presence of two subscribing witnesses.

FRANZ XAVER KOMAREK.
